DESIGN FOR A GOLF BALL

Walter Channing Burbank, New York, N. Y.

Application November 3, 1934, Serial No. 53,860

Term of patent 14 years

To all whom it may concern:

Be it known that I, Walter Channing Burbank, a citizen of the United States, residing at New York, county of New York, State of New York, have invented a new, original, and ornamental Design for a Golf Ball, of which the following is a specification, reference being had to the accompanying drawing, forming a part thereof.

Figure 1 is an elevational view of a golf ball, showing my new design.

Figure 2 is an elevational view of my new golf

ball taken on a different axis than that of Figure 1;

Figure 3 is a fragmentary cross sectional view taken transversely to the rib configuration; and

Figure 4 is a fragmentary cross sectional view taken longitudinally of the rib configuration.

I claim:

The ornamental design for a golf ball substantially as shown.

WALTER CHANNING BURBANK.
